US00D999199S

(12) **United States Design Patent** (10) **Patent No.:** **US D999,199 S**
(45) **Date of Patent:** ** *Sep. 19, 2023

(54) **CASE FOR ELECTRONIC COMMUNICATIONS DEVICE**

D669,071 S 10/2012 Akana et al.
D670,281 S 11/2012 Corpuz et al.
D670,293 S * 11/2012 Shimizu D14/440

(51) LOC (14) Cl. **14-03**

CLAIM

(52) U.S. Cl.

The ornamental design for a case for electronic communications device, as shown and described.

USPC **D14/250**

DESCRIPTION

(58) **Field of Classification Search**

USPC D14/203.3–203.7, 439, 251–253, 447, D14/217, 240, 238.1, 440, 248, 250; D13/103, 107–108, 119; D3/201, 218, D3/247, 249, 269, 273, 301, 303

CPC H04B 1/3888; A45C 11/00; A45C 13/02; A45C 2011/002; A45C 1/06; A45F 2200/0525; A45F 2005/026; A45F 2200/0516; H04M 1/0283; H04M 1/0202

See application file for complete search history.
